UNITED STATES PATENT OFFICE.

HUBERT EVERIST, OF SIOUX CITY, IOWA.

SUBGRADING MACHINE.

Application filed August 18, 1927. Serial No. 213,855.

The invention relates to a subgrading machine.

The object of the present invention is to improve the construction of subgrading machines and to provide a simple, practical and efficient subgrading machine of strong, durable and comparatively inexpensive construction equipped with a subgrader proper having a carriage adapted to run on the road forms at opposite sides of the subgrade or roadway and carrying rotary cutting members adapted to be driven by a tractor external to the subgrader and capable of advancing the subgrader as the cutting progresses whereby the road forms are subjected only to the weight and pressure of the subgrader proper and are relieved of the weight of the propelling means and the means for actuating the rotary cutting members and are thereby prevented from being destroyed or otherwise injured by the subgrading machine.

A further object of the invention is to provide a subgrading machine in which the traction will be upon the subgrade and which will be capable of adjusting the subgrader proper vertically to regulate the pressure of the same on the road forms and to produce a proper cutting action on the subgrade so that the latter may be accurately cut without injuring the road forms. Heretofore attempts have been made to mount the propelling mechanism and the power for operating the cutting members on the frame or carriage which travels on the road forms but this proved unsuccessful and impractical for the reason that the road forms are of a temporary character at best and unable to sustain the weight of such mechanism. Also attempts have been made to operate a subgrader by means of a post fixed in front of the work and a cable connected with the post and wound up by a power winch on the subgrader but this has also been found to be impractical and has been abandoned. The present machine accomplishes the results sought without danger of subjecting the road forms to excessive strain.

Also at the present time the roadway is roughed out by means which leaves three or four inches of dirt distributed over the roadway to be removed by hand. The current practice is to set the forms at the proper height and pick and shovel out the surplus material left by the rough graders. Naturally, the cost of this is high and fur-

thermore the work is exceedingly slow. It is also the object of the present invention to eliminate the foregoing objections to road grading and to provide a subgrading machine equipped with rotary cutting members arranged at an angle to the forward travel of the machine and adapted to constantly throw the dirt forward and to cause the dirt eventually to tail out at the back in windrows or piles along the subgrade in a finely ground form so that it may be readily handled by one or two men and thrown outside of the forms or spread to fill low spots in the event the grade is below normal. The angular arrangement of the rotary cutting members eliminates the longitudinal ridges left in the subgrade by transversely disposed rotary cutters which also spread the loose material the full width of the roadway making it very difficult and costly to remove such material.

Another object of the invention is to provide a road grading machine equipped with adjusting means for raising and lowering the subgrader proper not only for controlling the depth of the cut and the pressure on the side forms, but also for the purpose of elevating the subgrader a sufficient distance above the roadway to render the road grader highly portable and enable the same to be moved out of the way so that the road grading machine will not interfere with other road laying operations.

It is also an object of the invention to provide a road grading machine which will be capable of one man operation and in which the subgrader proper will have sufficient flexibility without liability of damaging the power mechanism.

Another object of the invention is to provide a subgrading machine which will be automatically guided by the road forms when operating as a subgrader and which may be readily guided when transferring the machine from one point or place to another.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit

or sacrificing any of the advantages of the invention.

In the drawings:

Figure 1 is a plan view of a subgrading machine constructed in accordance with this invention.

Fig. 2 is a side elevation of the same.

Fig. 3 is a transverse sectional view of the subgrading machine, the subgrader proper being shown in elevation.

Fig. 4 is a plan view of the subgrader proper.

Fig. 5 is a transverse sectional view taken centrally through the subgrader and illustrating the mechanism for raising and lowering the same.

Fig. 6 is a vertical sectional view taken substantially on the line 6—6 of Fig. 4 and illustrating the manner of mounting the shafts of the diagonally disposed cutting members.

Fig. 7 is a detail vertical, longitudinal, sectional view taken substantially on the line 7—7 of Fig. 1.

Fig. 8 is a detail horizontal, sectional view taken on the line 8—8 of Fig. 5.

In the accompanying drawings in which is illustrated the preferred embodiment of the invention, the road grading machine comprises in its construction a tractor 1 having rear tractor wheels 2 and provided with an arched elongated frame 3 composed of spaced forwardly converging frame members extending forwardly from the axle 4 of the rear tractor wheels 2 to a front axle 5. The front axle is equipped with front steering wheels 6 which are connected with a suitable steering mechanism comprising a downwardly and forwardly inclined longitudinally disposed steering shaft 7 having a steering wheel 8 at its upper rear end and provided at its lower end with a suitable crank element which is suitably connected with a steering rod 9 connecting the arms 10 of the spindles of the front steering wheels 6 in the usual manner. Any suitable steering mechanism may, of course, be employed and it is adapted for guiding the road grading machine when the same is being transported from one place to another or is being removed from the roadway so as not to interfere with other road operations.

The elongated frame of the tractor arches a subgrader proper comprising a carriage frame 11 extending across the roadway and provided with flanged wheels 12 arranged to run on the road forms 13. The carriage frame which may be of any desired construction is preferably composed of parallel channel members and suitable connecting members, the flanged wheels being mounted between extended terminals 14 of end connecting members 15 arranged in pairs as clearly illustrated in Figs. 1 and 4 of the drawings. The carriage carries the rotary

cutting members hereinafter described and the road forms on which the flanged wheels 12 run are subjected only to the weight of the carriage and the gearing for transmitting motion to the rotary cutting members from the tractor. Neither the power for moving the subgrader proper forwardly nor the power for driving the rotary cutting members is mounted upon the carriage so that excessive wear and tear on the road forms is eliminated.

The carriage frame is approximately oblong and it is connected with the tractor at opposite sides thereof by means of forwardly diverging links 16 pivoted at their rear ends in brackets 17 of the tractor and at their front ends in brackets 18 of the carriage frame 11. The brackets 17 are provided with recesses 19 to receive the rear terminals of the inclined links 16 which are secured to the brackets by transverse bolts 20. The front brackets 18 are also provided with recesses 21 and the front ends of the links 16 are secured to the brackets 18 by transverse bolts 22. The terminals of the links are bent at an angle to arrange them in parallelism with each other and with the road forms. The links 16 with the pivotal connections at their front and rear ends provide a flexible connection between the subgrader proper and the tractor so that the various adjustments of the subgrader will not result in any injury to the tractor. The brackets 18 are located in spaced relation with the extended frame of the tractor and at an intermediate point between the frame and the road forms so that power is equally applied to the subgrader proper at opposite sides of the center thereof. The tractor wheels 2 are arranged on the subgrade so that a firm engagement of the tractor wheels with the roadway is assured as well as a horizontal positioning of the tractor at the crown of the roadway. The front steering wheels are located in advance of the subgrader proper and will in practice be sufficiently flexibly connected with the frame so that any inequalities in the roadway will not affect the position of the tractor on the subgrade.

The subgrader proper is equipped with a plurality of angularly related rotary cutting members disposed diagonally of the roadway at approximately an angle of 45° to the longitudinal axis of the machine and comprising a pair of forwardly converging inner rotary cutting members 23, outer forwardly diverging rotary cutting members 24 and a centrally diagonally disposed rotary cutting member 25 located in rear of and at the space between the central rotary cutting members 125 and being of a length to cut that portion of the subgrade left uncut by the inner rotary cutting members through the spacing apart of the front ends thereof. The diagonally disposed angularly related rotary cutting 130

members which are arranged in overlapping relation so as to cover the entire surface of the roadway may, of course, be of any desired number and of different lengths and 5 they cover the entire surface of the subgrade between the road forms and the outer rotary cutting members 24 are disposed at a slight lateral inclination to give a crown to the roadway as clearly illustrated in Fig. 3 of 10 the drawings. The rotary cutting members may, of course, be adjusted to cut the desired amount of crown or to cut a perfectly level subgrade. Each rotary cutting member consists of a series of rotary cutters 26 consisting 15 of a central hub portion 27 and diametrically disposed arms 28 equipped at their front edges with cutting teeth 29 extending forwardly or in the direction of the rotation of the rotary cutting members and adapted to 20 throw the cut dirt forwardly and the material cut from the roadway to form the subgrade is cut in an extremely fine condition and will eventually tail out at the back in windrows or piles along the subgrade and yet distribute 25 over the entire surface of the subgrade. This dirt in its fine condition and the discharge of the material in rows or piles will enable the matter to be readily handled by one or two men at a minimum cost. The cut material 30 may be used for making fills in portions of the roadway below the normal grade or otherwise disposed of. No claim is made in the present application to the particular construction of the rotary cutters of the cutting members as this forms the subject matter 35 of my Patent No. 1,661,692, granted March 6, 1928. The rotary cutters are fixed to shafts which are mounted in adjustable self-aligning bearings adapted to enable the 40 different rotary cutting members to be arranged at various heights so that any practical subgrade contour can be finished automatically.

Power is transmitted from the tractor to 45 the rotary cutting members by means of sprocket gearing located at one side of the tractor and comprising a sprocket pinion 30 connected with the motor of the tractor, a sprocket gear 31 of a driving speed reducing 50 jack shaft 32 and a sprocket chain 33 arranged on and meshing with the sprocket pinion and the sprocket gear. The driving speed reducing jack shaft 32 is journaled in suitable bearings of the carriage frame of 55 the subgrader proper and it is disposed transversely thereof and centrally of the same at the rear portion of the said carriage frame. The driving speed reducing jack shaft 32 is connected by sprocket gearing 60 with a main drive shaft 34 comprising a sprocket pinion 35 mounted on the speed reducing jack shaft 32, a sprocket gear 36 fixed to the main drive shaft 34 and a sprocket chain 37 arranged on and meshing with 65 the sprocket pinion 35 and the sprocket gear

36. The main drive shaft 34 is journaled in suitable bearings of the carriage frame 11 and is disposed transversely thereof slightly in rear of the center of the same as clearly illustrated in Fig. 4 of the drawings. The 70 sprocket gearing forms a flexible connection between the tractor and the subgrader proper and is yieldable with the pivoted links to allow independent movement of the tractor and the subgrader proper. 75

The main drive shaft is equipped at its ends with spur gear wheels 38 which mesh with spur gear wheels 39 fixed to the inner rear ends of forwardly diverging shanks 40 journaled in suitable bearings of the carriage so and equipped at their front ends with spur pinions 41 which mesh with spur pinions 42 of front diagonally disposed shafts 43 arranged at right angles to the forwardly diverging shafts 40. The gears 38, 39, 41 and 85 42 are beveled gears and the diagonally disposed shafts 40 and 43 are positively geared by spur gearing with the main drive shaft and constitute driving gearing and are connected by sprocket gearing with the rotary 90 cutting members for rotating the same. The sprocket gearing hereinafter described provide a flexible driving connection between the driving shafts and the rotary cutting members to allow for independent movement 95 and adjustment of the rotary cutting members and the number of the links of the sprocket chains hereinafter described may, of course, be varied to permit any adjustment of the rotary members as will be readily understood. The forwardly diverging drive shafts 40 are connected with the shafts 44 of the outer rotary cutting members by sprocket gearing comprising a sprocket pinion 45 mounted on the shaft 40 a sprocket gear 46 100 mounted on the shaft 44 and a sprocket chain 47 arranged on the sprocket pinion 45 and the sprocket gear 46 and meshing with the same and transmitting motion from the drive shaft 40 to the shaft 44 of the outer 105 rotary cutting member. The inner rotary cutting members 23 are connected with the short diagonally disposed drive shafts 43 by sprocket gearing comprising a sprocket pinion 48 mounted on the drive shaft 43 a 110 sprocket gear wheel 49 mounted on the shaft 50 of the inner rotary cutting member 23 and a sprocket shaft 51 arranged on the sprocket pinion 48 and the sprocket gear 49 and meshing with the same as clearly shown 115 in Fig. 4 of the drawings. The central diagonally disposed rotary cutting member is connected with the left hand diagonally disposed drive shaft 40 by means of sprocket 120 gearing consisting of a sprocket pinion 52 mounted on the left hand drive shaft 40 a sprocket gear 53 fixed to the front end of the shaft 54 of the central rotary cutting member and a sprocket chain 55 arranged on 125 and meshing with the sprocket pinion 52 and 130

the sprocket gear 53. The main centrally arranged transverse drive shaft 34 and the diagonally disposed angularly related side drive shafts 40 and 43 are adapted to be mounted in rigid or fixed bearings of the carriage of the subgrader proper and they afford positive means for driving the adjustable diagonally disposed rotary cutting members which are connected with the said driving shafts by flexible gearing which will admit of the adjustment of the rotary driving members.

The subgrader proper is adjustably connected with the tractor by means of opposite jacks 56 mounted on the arched frame 3 of the tractor centrally of the said frame 3 and at opposite sides thereof and comprising vertically disposed screws 57 connected with the carriage frame and engaged by gear nuts 58 mounted in brackets 59 of extensions 60 of the arched frame between upper and lower thrust bearings 61 and 62. The screws 57 are connected at their lower ends with pedestals 63 which may be hinged at the bottom to the carriage frame. Any suitable hinge connection may be provided and the pivots or pintles thereof are disposed transversely with relation to the frame of the machine and permit a relative pivotal or tilting movement between the main frame of the tractor and the carriage frame of the subgrader proper. The thrust bearings may be ball bearings or roller bearings of any desired construction and the bracket 59 is approximately inverted U-shaped and composed of spaced sides and a connecting top portion the sides being preferably shaped as shown to taper the upper and lower portions of the bracket and provide the necessary clearance for the gear nuts. The gear nuts consist of gear wheels for interiorly threaded hubs engaging the threads of the screws 57. The gear nuts 58 mesh with spur pinions 65 fixed to the ends of a transverse shaft 66 journaled in suitable bearings 67 of the extensions of the arched frame of the tractor and provided with a hand wheel 67' by means of which the shaft 66 may be rotated for operating the jacks to raise or lower the subgrade proper. If desired the jacks may be provided with a spring suspension of any desired character for yieldably connecting the subgrader proper with the screws of the jacks for cushioning the action of the jacks. The jacks are adapted to be adjusted to raise or lower the subgrader proper for arranging the same at the proper cutting elevation and to adjust the pressure of the subgrader on the road forms. Also the jacks are adapted to enable the subgrader to be lifted clear of the roadway so that the entire machine may be moved from the line of work. This will enable the subgrading machine to be readily moved out of the way so as not to interfere with other road laying operations. The

jacks are adapted to produce either an upward thrust of the gear nuts against the upper bearings or a downward thrust of the gear nuts against the lower bearings so that the subgrader proper may be made to support the weight of the forepart of the tractor or the tractor support the entire weight of the subgrader proper. This will enable the pressure to be controlled so that the subgrader when in operation will engage the roadway and the road forms with the desired pressure. This will enable the road cutting and subgrading operations to be accurately performed without excessive wear and tear on the road forms. In operation the steering device is not effective as the machine is guided by the flanged wheels on the road forms. When the subgrader is lifted from the forms the steering wheel operates the front wheels and the entire mechanism can be guided anywhere under its own power.

In Fig. 5 of the drawings is illustrated a yieldable flexible connection between the vertical screws 57 and the pedestals 63 which are provided with vertical chambers 68 receiving coiled springs 69 arranged in pairs and located above and below collars 70 carried by the vertical screws 57. The lower portions 71 of the vertical screws are smooth and extend through openings 72 of caps 73 and openings 74 in the bottom walls of the chambers 68 of the pedestals. The caps 73 are suitably secured to the pedestals and constitute the top walls thereof and are readily removable to afford access to the springs. The openings 72 in the caps and the openings 74 in the bottom walls of the said chamber 68 are of sufficient size to permit lateral movement of the parts which together with the relative vertical movement of the pedestals and the screws will provide a pivotal action and a hinge connection between the screws and the pedestals. The springs produce a cushioning action on the rotary cutting members as well as a spring suspension for the same.

The diagonal shafts of the rotary cutting members may be mounted in any form of adjustable bearing and in Fig. 6 of the drawings is illustrated one form of bearing comprising a suitable casing 75 having an annular chamber, the circumferential wall 76 of which forms one race or groove for anti-friction balls 77. The other groove or race is formed by a collar or disk 78 mounted on the shaft of the rotary cutting member and provided in its periphery with a transversely concave groove 79. This form of ball bearing will permit a relative rocking movement of the shafts of the rotary cutters but any other form of bearing may be provided for mounting the ends of the shafts of the diagonally disposed rotary cutting members.

The adjustment of the bearing is obtained

by means of a vertical series of shims 80 arranged one upon another and interposed between the bearing housing or casing 75 and the carriage frame 11. Any number of 5 the shims 80 may be employed and by varying the number of the shims 80 the adjustment is effected. The shims and the casing or housing of the bearing are secured together by parallel bolts piercing the shims, 10 the casing or housing 75 and the bottom flanges of the channel members of the carriage frame 11.

What is claimed is:

1. A subgrading machine including a carriage extending across the roadway and provided with wheels arranged to run on road forms, said carriage being provided with rotary cutting members, a tractor having an extended frame arching the carriage 20 frame and provided with front steering wheels located in advance of the carriage frame, said tractor being provided at the rear end with tractor wheels arranged to run on the subgrade, flexible means for connecting the tractor with the carriage frame for propelling the carriage and flexible gearing for connecting the rotary cutter members with the tractor for operating the said cutting members.
2. A subgrading machine including a carriage extending across the roadway, said carriage being provided with rotary cutting members, a tractor having an extended frame arching the carriage frame and provided with front steering wheels located in 30 advance of the carriage frame, said tractor being provided at the rear end with tractor wheels arranged to run on the subgrade, and links located in rear of the carriage and connecting the tractor with the said carriage and provided at their ends with flexible joints, and flexible gearing for connecting the rotary cutter members with the tractor for operating the said cutting members.
3. A subgrading machine including a carriage extending across the roadway, said carriage being provided with rotary cutting members, a tractor having an extended frame arching the carriage frame and provided with front steering wheels located in 40 advance of the carriage frame, said tractor being provided at the rear end with tractor wheels arranged to run on the subgrade, front brackets mounted on the carriage at opposite sides of the tractor in spaced relation with the same, rear brackets secured to the tractor at opposite sides thereof and forwardly diverging links hinged at their rear ends to the rear brackets and at their front ends to the front brackets for flexibly connecting the carriage with the tractor, and flexible gearing for connecting the rotary cutter members with the tractor for operating the said cutting members.
4. A subgrading machine including a carriage 45 adapted to extend across a roadway, rotary cutting members carried by the carriage, a tractor having an extended frame arching the carriage and provided in advance of the same with front steering wheels, said tractor having traction wheels located in rear of the carriage to run on the subgrade, flexible means for connecting the carriage with the tractor for propelling the carriage, and flexible gearing connecting the rotary cutting members with the tractor, spaced jacks mounted on the tractor frame at opposite sides thereof and connected with the carriage and gearing connecting the jacks for simultaneously operating the same to raise and lower the carriage out of and into position and for controlling the pressure of the carriage.
5. A subgrading machine including a carriage 50 adapted to extend across a roadway, rotary cutting members carried by the carriage, a tractor having an extended frame arching the carriage and provided in advance of the same with front steering wheels, said tractor having traction wheels located in rear of the carriage to run on the subgrade, flexible means for connecting the carriage with the tractor for propelling the carriage, flexible gearing connecting the rotary cutting members with the tractor, spaced jacks mounted on the tractor frame at opposite sides thereof and connected with the carriage and gearing connecting the jacks for simultaneously operating the same to raise and lower the carriage out of and into position and for controlling the pressure of the carriage.
6. A subgrading machine including a carriage 55 adapted to extend across a roadway, rotary cutting members carried by the carriage, a tractor having an extended frame arching the carriage and provided in advance of the same with front steering wheels, said tractor having traction wheels located in rear of the carriage to run on the subgrade, flexible means for connecting the carriage with the tractor for propelling the carriage, flexible gearing connecting the rotary cutting members with the tractor, spaced jacks located at opposite sides of the tractor frame and comprising vertically adjustable screws connected with the carriage, and gear nuts mounted on the tractor frame and engaging the threads of the screws, and gearing for simultaneously rotating the gear nuts.
7. A subgrading machine including a carriage 60 adapted to extend across a roadway, rotary cutting members carried by the carriage, a tractor having an extended frame arching the carriage and provided in advance of the same with front steering wheels, said tractor having traction wheels located in rear of the carriage to run on the subgrade, flexible means for connecting the carriage with the tractor for propelling the carriage, flexible gearing connecting the rotary cutting members with the tractor, spaced jacks mounted on the tractor frame at opposite sides thereof and connected with the carriage and gearing connecting the jacks for simultaneously operating the same to raise and lower the carriage out of and into position and for controlling the pressure of the carriage.

- jacks mounted on the tractor frame at opposite sides thereof and comprising vertically adjustable screws connected with the carriage, gear nuts mounted on the tractor frame and engaging the threads of the screws, a transverse shaft mounted on the tractor frame and extending across the same and provided with gears meshing with the gear nuts, and means for rotating the said shaft.
- 10 8. A subgrading machine including a carriage adapted to extend across a roadway, rotary cutting members carried by the carriage, a tractor having an extended frame arching the carriage and provided in advance of the same with front steering wheels, said tractor having traction wheels located in rear of the carriage to run on the subgrade, flexible means for connecting the carriage with the tractor for propelling the carriage, flexible gearing connecting the rotary cutting members with the tractor, adjusting means for raising and lowering the carriage comprising bearing brackets mounted on the carriage at opposite sides thereof, vertical screws extending through the bearing brackets and connected at their lower ends with the carriage, gear nuts arranged in the bearing brackets and engaging the threads of the screws, and a shaft extending across the frame of the tractor and having gears meshing with the gear nuts for simultaneously rotating the same.
- 15 9. A subgrading machine including a carriage adapted to extend across a roadway, rotary cutting members carried by the carriage, a tractor having an extended frame arching the carriage and provided in advance of the same with front steering wheels, said tractor having traction wheels located in rear of the carriage to run on the subgrade, flexible means for connecting the carriage with the tractor for propelling the carriage, flexible gearing connecting the rotary cutting members with the tractor, and adjusting means for raising and lowering the carriage comprising bearing brackets mounted on the carriage at opposite sides thereof, vertical screws extending through the bearing brackets and connected at their lower ends with the carriage, gear nuts arranged in the bearing brackets and engaging the threads of the screws, upper and lower thrust bearings mounted in the brackets and arranged above and below the gear nuts, a transverse shaft extending across the tractor frame and having gears meshing with the gear nuts, and manually operable means for rotating the shaft.
- 20 10. A subgrading machine including a carriage extending across the roadway, rotary cutting members carried by the carriage and arranged diagonally with relation to the roadway in spaced overlapping relation and having rotary cutters arranged to throw the cut material continuously forward and cause a tailing of the cut material in windrows or ridges, and a tractor having means external to the carriage for propelling the same and for driving the rotary cutting members.
- 25 11. A subgrader machine including a carriage extending across the roadway, rotary cutting members carried by the carriage and arranged diagonally with relation to the roadway in spaced overlapping relation and having rotary cutters arranged to throw the cut material continuously forward and cause a tailing of the cut material in windrows or ridges, and a tractor having tractor wheels arranged to run on the subgrade, said tractor having flexible means for propelling the carriage and for driving the rotary cutting members.
- 30 12. A subgrading machine including a carriage extending across the roadway, rotary cutting members carried by the carriage and arranged diagonally with relation to the roadway in spaced overlapping relation and having rotary cutters arranged to throw the cut material continuously forward and cause a tailing of the cut material in windrows or ridges, a tractor having tractor wheels arranged to run on the subgrade, said tractor having flexible means for propelling the carriage and for driving the rotary cutting members, and adjusting means connecting the carriage with the tractor for varying the pressure of the carriage and for lowering the same into position and for raising the same out of position.
- 35 13. A subgrading machine including a carriage extending across the roadway, rotary cutting members carried by the carriage and arranged diagonally with relation to the roadway in spaced overlapping relation and having rotary cutters arranged to throw the cut material continuously forward and cause a tailing of the cut material in windrows or ridges, and a tractor having an extended frame arching the carriage, said tractor being provided in advance of the carriage with steering wheels and in rear of the carriage with tractor wheels arranged to run on the subgrade, and flexible means for connecting the tractor with the carriage to propel the latter and with the rotary cutting members for driving the same.
- 40 14. A subgrading machine including a carriage adapted to extend across a roadway and provided with wheels, outer forwardly diverging diagonally disposed rotary cutting members, inner forwardly converging rotary cutting members spaced from the rear ends of the outer cutting members, the latter being arranged in overlapping relation with the inner cutting members, and a central diagonally disposed rotary cutting member arranged in rear of and in overlapping relation with the front ends of the inner rotary cutting members.
- 45 50 55 60 65 70 75 80 85 90 95 100 105 110 115 120 125 130

15. A subgrading machine including a carriage adapted to extend across a roadway, outer forwardly diverging diagonally disposed rotary cutting members, inner forwardly converging rotary cutting members spaced from the rear ends of the outer cutting members, the latter being arranged in overlapping relation with the inner cutting members, a central diagonally disposed rotary cutting member arranged in rear of and in overlapping relation with the front ends of the inner rotary cutting members, a centrally arranged main driving shaft, forwardly diverging side driving shafts located at opposite sides of the main driving shaft and extending in advance of the same, outer driving shafts extending rearwardly at the outer ends of the side driving shafts at right angles thereto, beveled gears mounted on the said shafts and arranged in pairs and meshing with each other and sprocket gearing connecting the rotary cutting members with the adjacent shafts, a tractor having an extended frame and arching the carriage and provided in advance of the same with front steering wheels and having rear tractor wheels located in rear of the carriage and arranged to run on the subgrade, sprocket gearing connecting the tractor with the main driving shaft, and forwardly diverging links located at opposite sides of the tractor in rear of the carriage and pivotally connected at their front ends to the said carriage and at their rear ends to the tractor.

16. A subgrading machine including a carriage adapted to extend across a roadway, outer forwardly diverging diagonally disposed rotary cutting members, inner forwardly converging rotary cutting members spaced from the rear ends of the outer cutting members, the latter being arranged in overlapping relation with the inner cutting members, a central diagonally disposed rotary cutting member arranged in rear of and in overlapping relation with the front ends of the inner rotary cutting members, a centrally arranged main driving shaft forwardly diverging side driving shafts located at opposite sides of the main driving shaft and extending in advance of the same, outer driving shafts extending rearwardly at the outer ends of the side driving shafts at right angles thereto, beveled gears mounted on the said shafts and arranged in pairs and meshing with each other and sprocket gearing connecting the rotary cutting members with the adjacent shafts, a tractor having an extended frame and arching the carriage and provided in advance of the same with front steering wheels and having rear tractor wheels located in rear of the carriage and arranged to run on the subgrade, sprocket gearing connecting the tractor with the main driving shaft, and flexible means for connecting the tractor with the carriage for propelling the same.

17. A subgrading machine including a carriage adapted to extend across a roadway and provided with wheels arranged to run on road forms, outer forwardly diverging diagonally disposed rotary cutting members, inner forwardly converging rotary cutting members spaced from the rear ends of the outer cutting members, the latter being arranged in overlapping relation with the inner cutting members, a central diagonally disposed rotary cutting member arranged in rear of and in overlapping relation with the front ends of the inner rotary cutting members, a centrally arranged main driving shaft, forwardly diverging side driving shafts located at opposite sides of the main driving shaft and extending in advance of the same, outer driving shafts extending rearwardly at the outer ends of the side driving shafts at right angles thereto, beveled gears mounted on the said shafts and arranged in pairs and meshing with each other and sprocket gearing connecting the rotary cutting members with the adjacent shafts, a tractor having an extended frame and arching the carriage and provided in advance of the same with front steering wheels and having rear tractor wheels located in rear of the carriage and arranged to run on the subgrade, sprocket gearing connecting the tractor with the main driving shaft, and flexible means for connecting the tractor with the carriage for propelling the same.

18. A subgrading machine including a carriage adapted to extend across a roadway, rotary cutting members carried by the carriage, a tractor having an extended frame arching the carriage and provided in advance of the same with steering wheels and having traction wheels located in rear of the carriage to run on the subgrade, flexible means for connecting the rotary cutting members with the tractor, and spaced jacks located at opposite sides of the tractor frame and comprising vertically adjustable screws, nuts mounted on the tractor frame and engaging the threads of the screws, pedestals mounted on the carriage and receiving the lower portions of the said screws, and springs arranged in pairs in the pedestals and forming a yieldable connection between the screws and the pedestals to provide a spring suspension and a cushioning action for the carriage.

19. A subgrading machine including a carriage frame, a shaft, rotary cutting members mounted on the shaft self-aligning bearings receiving the ends of the shaft, and adjustable means arranged exteriorly of the bearings for connecting the bearings with the carriage frame, said means including a plurality of shims adapted to be varied in number to effect an adjustment of the shaft.

20. A subgrading machine including a carriage provided with wheels, outer forwardly diverging diagonally disposed rotary cutting members, inner forwardly converging rotary cutting members spaced from the rear ends of the outer cutting members, the latter being arranged in overlapping relation with the inner cutting members, a central diagonally disposed rotary cutting member arranged in rear of and in overlapping relation with the front ends of the inner rotary cutting members, a centrally arranged main driving shaft, forwardly diverging side driving shafts located at opposite sides of the main driving shaft and extending in advance of the same, outer driving shafts extending rearwardly at the outer ends of the side driving shafts at right angles thereto, beveled gears mounted on the said shafts and arranged in pairs and meshing with each other and sprocket gearing connecting the rotary cutting members with the adjacent shafts, a tractor having an extended frame and arching the carriage and provided in advance of the same with front steering wheels and having rear tractor wheels located in rear of the carriage and arranged to run on the subgrade, sprocket gearing connecting the tractor with the main driving shaft, and forwardly diverging links located at opposite sides of the tractor in rear of the carriage and pivotally connected at their front ends to the said carriage and at their rear ends to the tractor.

lation with the inner cutting members, and means carried by the said carriage for rotating the said cutting members.

21. A subgrading machine including a tractor having an extended frame and provided with front steering wheels and having rear traction wheels, a carriage located beneath the frame of the tractor and provided with wheels, spaced jacks located at opposite sides of the tractor frame and comprising vertically adjustable screws connected with the carriage, and nuts mounted on the tractor frame and engaging the threads of the screws, and manually operable gearing for rotating the nuts to operate the jacks.

22. A subgrading machine including a carriage extending across the roadway, said carriage being provided with rotary cutting members, a tractor having an extended frame arching the carriage frame and provided with front steering wheels located in advance of the carriage frame, said tractor being provided at the rear end with tractor wheels arranged to run on the subgrade, flexible means for connecting the tractor with the carriage frame for propelling the carriage and flexible gearing for connecting the rotary cutter members with the tractor for operating the said cutting members.

23. A subgrading machine including a carriage adapted to extend across a roadway, outer forwardly diverging diagonally disposed rotary cutting members, inner forwardly converging rotary cutting members

spaced from the rear ends of the outer cutting members, the latter being arranged in overlapping relation with the inner cutting members, a central diagonally disposed rotary cutting member arranged in rear of and in overlapping relation with the front ends of the inner rotary cutting members, a centrally arranged main driving shaft, forwardly diverging side driving shafts located at opposite sides of the main driving shaft and extending in advance of the same, outer driving shafts extending rearwardly at the outer ends of the side driving shafts at right angles thereto, beveled gears mounted on the said shafts and arranged in pairs and meshing with each other and sprocket gearing connecting the rotary cutting members with the adjacent shafts, a tractor having an extended frame and arching the carriage and provided in advance of the same with front steering wheels and having rear tractor wheels located in rear of the carriage and arranged to run on the subgrade, sprocket gearing connecting the tractor with the main driving shaft, and forwardly diverging links located at opposite sides of the tractor in rear of the carriage and pivotally connected at their front ends to the said carriage and at their rear ends to the tractor.

In testimony whereof I have hereunto set my hand.

HUBERT EVERIST.
